DISASSEMBLABLE TREE BALL TRANSPORTER

Eugene B. Everly, Denver, Colo., assignor to
Lew Hammer, Inc.

Filed Mar. 24, 1971, Ser. No. 127,866

Term of patent 14 years

Int. Cl. D15—03

U.S. Cl. D35—1

FIG. 1 is an exploded view of a disassemblable tree ball transporter;

FIG. 2 is a perspective view of the disassemblable tree ball transporter in assembled condition;

FIG. 3 is a top plan view thereof; and

FIG. 4 is a side elevational view thereof.

I claim:

The ornamental design of a disassemblable tree ball transporter, substantially as shown and described.
